DOOR INDICATING DEVICE

Rudolph Wirth, New York, N. Y.

Application January 24, 1948, Serial No. 4,172

13-Claims. (Cl. 40—66)

1

This invention relates to door indicating devices, more particularly to manually manipulable indicators on doors adapted to expose to view a sign, symbol or message.

There is a wide field for devices of the above-mentioned category in hotels, apartment houses and offices, where it may be necessary to inform prospective visitors, employees or other callers as to whether or not the premises may be entered. Although various devices have been employed for such purposes, bearing such messages as "Do Not Disturb," "Open," "Out to Lunch," etc., they generally are built-in parts of the door locking or opening mechanism, or entirely separate units in no way connected with such mechanism and hence requiring special manipulative effort. It is primarily within the contemplation of my invention to combine the advantages of both said types of indicators by providing a device that, although operable by the door opening mechanism, nevertheless is not a built-in or integral component thereof.

In the above-mentioned aspect of my invention, it is an important object to enable the device to be readily attached to existing doors without altering the construction of the door opening mechanism, and without the necessity of mutilating or making any substantial changes in the door proper.

It is another object of my invention to enable the indicator to be selectively moved between at least two positions by a simple operation of the door knob.

Another object is to enable the sign carried by the indicator to be visible, if desired, both from the inside and outside of the door.

Still another object of this invention is to provide an obstruction to the keyhole when the sign is in a predetermined position, thereby preventing a building employee, for example, from entering a room if the message on the sign is inadvertently overlooked.

A further object is to provide a device capable of performing all the above-mentioned functions, and which will nevertheless be both presentable in appearance and simple to fabricate.

Other objects, features and advantages will appear from the drawing and the description hereinafter given.

Referring to the drawings,

Figure 1 is a fragmentary end view of a door provided with a preferred form of my invention, portions being shown partly in section for clarity.

Figure 2 is a front view of the outside escutcheon plate and knob of the door of Fig. 1.

Figure 3 is a somewhat enlarged perspective view of the actuating mechanism disposed behind the escutcheon, the sign and carrier bar therefor being fragmentarily shown.

2

Figure 4 is a section of Fig. 3 taken along line 4—4.

Figure 5 is a front view of the actuating mechanism of Fig. 3, the cam plate being shown in neutral position, the sign and its carrier bar being shown by dot-dash lines in their lowered position.

Figure 6 is a view like Fig. 5, the parts being shown in their respective positions when the sign is in its lowered or exposed position.

Figure 7 is also a view like Fig. 5, the parts being shown in their respective positions when the sign is in its raised or hidden position.

Figure 8 is a fragmentary perspective view of the escutcheon and associated parts in the region of its window.

Figure 9 is a section of Fig. 8 taken substantially along line 9—9 thereof.

Figure 10 is a section of Fig. 8 taken substantially along line 10—10 thereof.

Figure 11 is a fragmentary perspective view of the front and rear sign carrying bars and the key-hole portions of the corresponding escutcheon plates, the door and casings being removed, said bars being of slightly modified form; and

Figure 12 is a fragmentary view substantially like Fig. 5, but showing the form of sign carrying bar of Fig. 11, the neutral position of the square latch-actuating shaft being angular.

In the preferred form of my invention illustrated, the door 15 contains the locking plate 16, the conventional key-operated bolt 17, the conventional spring-retractable latch 18 operatively connected, in known manner, to the conventional square shank door knob shaft 19 operatively attached to the two knobs 20 and 21 at the inner and outer sides, respectively, of the door 15. The actuating mechanism for the bolt 17 and latch 18, and the latter's connection to the shaft 19, are omitted, since they are of common construction, known to those skilled in the art, and need not be described for an understanding of the invention. The escutcheon plates 22 and 23, to be hereinafter described, contain the keyholes 24 and 25, respectively, and these are in registry with conventional keyholes at 26 and 27, operatively associated with bolt 17, so that upon the insertion of a key in either the front or back keyholes, the said bolt 17 could be actuated in known manner.

The said escutcheon plates 22 and 23 have peripheral flanges 28 and 29, respectively, the front walls 30 and 31 being sufficiently spaced from the adjacent surfaces of the door as to accommodate the actuating mechanism for the indicator, each escutcheon shell containing a casing 32, a reciprocable sign carrying bar 33 slidably movable through the casing's top and bottom slots 34 and 35, respectively, a spring 36 mounted on the rear wall 37 of the casing and

yieldably pressing against the front surface 38 of the bar 33 to frictionally hold it in place when in its upper position, and the sign 39 supported between the pressed-out prongs 40 and the upper rim 41 of the bar, and the cam plate 42.

The shaft 19 extends through and engages the walls of the square aperture 43 of the cam plate 42; and where the inner and outer portions of the door are provided with indicating means, as in the embodiment illustrated, the said shaft extends through and rotatably supports both cam plates. The axial portion of the cam, that is, the portion 44 surrounding the shaft 19, is depressed rearwardly into the vertical slot 45 of the bar 33 and is slidably engageable with the side walls thereof, whereby the bar 33 will be guided along its vertical path by said depressed portion 44.

The lower portion of the cam 42 contains the aperture 46 containing an upper and a lower curved cam surface 47 and 48, respectively, said cam surfaces joining at upper lateral recess 49 and lower lateral recess 50, said lateral recesses being at opposite sides of the aperture 46. The portion 47a of the upper cam surface 47 that is to the left of center-line C—C of square shaft 19 is closer to the axis of said shaft than the right portion 47b of the cam surface, and portion 48a of lower cam surface 48 that is to the left of said centerline C—C is also closer to said axis than the left portion 58b.

Affixed to bar 33 and extending forwardly therefrom into aperture 46 is the follower pin 51 and roller 52 mounted thereover, said roller being engageable with said cam surfaces and the walls of said recesses. The side walls of the casting contain slots 53 and 54 to accommodate the peripheral portion 55 of the cam when in its extreme limiting positions, the slot 35 accommodating said peripheral portion when the cam is in its neutral position, as shown in Figures 3 and 5.

It will be further noted that the escutcheon plates are secured to the door 15 by fasteners 56, and are provided with apertures 57 to permit the shaft 19 and associated parts to extend therethrough, the member 58 being in abutting engagement with the outer surfaces of the escutcheons adjacent the apertures 57. The wall 37 of casing 32 also contains an opening 37a to permit the shaft 19 to pass therethrough.

When the shaft 19 is in its neutral position, as shown in Fig. 5, the sign 39 can either be in its raised or invisible position, as shown in full lines, or in its lowered or visible position, as shown by dot-dash lines. In the former case the follower 52 is in engagement with upper cam surface 47, and in the latter case it is in engagement with the lower cam surface 48.

When the shaft 19 is, by a turning of the door knob, rotated in a clockwise direction to the position shown in Fig. 6, portion 47b of upper cam surface 47 will, because of its downwardly sloping contour, force the follower 52 downwardly to lower it into lateral recess 50 and into engagement with the lower cam surface 48. This action will cause a lowering of bar 33, to expose the sign 39 to view through the window 59 in the escutcheon. When the door knob is released and the shaft caused to return to its neutral position as indicated in Fig. 5, the follower 52, in engagement with cam surface portion 48b, will remain in the same horizontal position, since said cam portion 48b is an arc of a circle having the axis 60 of shaft 19 as its center. Accordingly, the bar 33 and sign 39 will remain undisturbed.

If it is desired to raise the sign above the

window to its invisible position indicated in Fig. 7, the shaft 19 is turned in a counterclockwise direction by operatively rotating the knob, whereby the upwardly sloping portion 48a of lower cam surface 48 will elevate the follower 52 until it is disposed within lateral recess 49. This action causes the desired upward movement of the bar 33 and the sign 39. And when the door knob is again released and the shaft 19 caused to return to its neutral position, the follower 52 will ride on portion 47a of the upper cam surface; and since said portion 47a is an arc having the axis 60 of shaft 19 as its center, the bar and the sign will remain undisturbed in its elevated position.

It is thus apparent that the two operative positions of the sign 39 can be manually effected merely by turning the door knob, there being no additional operations necessary.

As a further assurance that the occupant of a room will not be disturbed when a "Do Not Disturb" or equivalent sign is in its exposed position, one of the keyholes, preferably the outer one, can be obstructed in the manner indicated in Figures 1 and 11. The lower portion of the outer bar 33a (Fig. 11) is provided with a narrow depending strip 61a (outer bar 33 of Fig. 1 having a similar strip 61). When the bar 33a is in its lower position, the strip 61a partially obstructs the adjacent keyhole 24a in the escutcheon plate 22a, just as 61 obstructs keyhole 24 of Figures 1 and 2. When the sign carrying bar is in its raised position, the said strip 61 or 61a is above the corresponding keyhole, in its unobstructing position. And as clearly shown in Figure 11, the inside bar 33b has no depending strip, and hence can not obstruct the inner keyhole at any time. Thus, when the sign is down and exposed to view, a failure to observe the sign will nevertheless prevent a maid or other employee from unlocking the door.

The form of bar shown in Fig. 11 is further provided with two additional holes 62 and 63 flanking the central hole through which pin 51a extends. This arrangement is of value when applied to a shaft 19a (Fig. 12) which, in its neutral position, happens to have its center line L—L at an inclination to the vertical. Under the conditions indicated in Fig. 12, the pin 52a is inserted in hole 62, rather than in the middle hole. Once this setting is made, the device operates in the manner above set forth.

In the above description, the invention has been disclosed merely by way of example and in preferred manner; but obviously many variations and modifications may be made therein which will still be comprised within its spirit. It is to be understood, therefore, that the invention is not limited to any specific form or manner of practicing same, except insofar as such limitations are specified in the appended claims.

I claim:

1. In an indicating device for use with a door having a knob and a shaft connected thereto of the type where the knob and shaft are rotatable between an intermediate neutral position and two opposite extreme positions, the combination of a reciprocable bar movable between two limiting positions, a sign carried by the bar; a cam fixedly mounted on the shaft and containing one upper and one lower arcuate surface, said arcuate surfaces being at opposite sides of the cam and having their respective centers at the axis of rotation of the cam; an upper operative surface on the cam adjacent the upper arcuate surface and

sloping downwardly and outwardly therefrom, a lower operative surface adjacent the lower arcuate surface and sloping upwardly and outwardly therefrom, said operative surfaces being at opposite sides of the cam; and a follower attached to the bar and engageable with said surfaces, the follower being engageable with the said upper operative cam surface when the knob is rotated from its neutral position to one of its extreme positions to operatively lower the bar, the follower being engageable with the said lower arcuate surface when the knob is returned to its neutral position to maintain the bar against movement; the follower being engageable with the lower operative surface when the knob is moved to the other of its extreme positions to operatively raise the bar, the follower being engageable with the upper arcuate surface when the knob is returned to its neutral position to maintain the bar against movement.

2. An indicating device according to claim 1, further provided with an escutcheon adapted for attachment to the door and in overlying relation to said bar and cam, said escutcheon having an opening adapted to permit the passage therethrough of said shaft.

3. An indicating device according to claim 2, the escutcheon covering the entire bar and the sign in both of said limiting positions, the escutcheon containing a window in registry with the sign in only one of said two limiting positions.

4. An indicating device according to claim 3, the escutcheon having a flanged periphery forming a shell completely enclosing therein said cam, bar and sign.

5. In an indicating device for use with a door having a knob and a shaft connected thereto of the type where the knob and shaft are rotatable between an intermediate neutral position and two opposite extreme positions, the combination of a reciprocable bar movable between two limiting positions, a sign carried by the bar; a cam fixedly mounted on the shaft and having an apertured portion therein containing a plurality of cam surfaces, said surfaces comprising one upper and one lower arcuate surface, said arcuate surfaces being at opposite sides of the cam and having their respective centers at the axis of rotation of the cam, an upper operative surface adjacent the upper arcuate surface and sloping downwardly and outwardly therefrom, a lower operative surface adjacent the lower arcuate surface and sloping upwardly and outwardly therefrom, said operative surfaces being at opposite sides of the cam; and a follower attached to the bar and engageable with said surfaces, the follower being engageable with the said upper operative cam surface when the knob is rotated from its neutral position to one of its extreme positions to operatively lower the bar, the follower being engageable with the said lower arcuate surface when the knob is returned to its neutral position to maintain the bar against movement, the follower being engageable with the lower operative surface when the knob is moved to the other of its extreme positions to operatively raise the bar, the follower being engageable with the upper arcuate surface when the knob is returned to its neutral position to maintain the bar against movement.

6. In an indicating device of the class described, the combination according to claim 5, the upper and lower surfaces joining at upper and lower lateral recesses at opposite sides of the aperture, the follower being disposed within said respective

recesses when the knob and cam are in their extreme positions.

7. In an indicating device of the class described, the combination according to claim 6, the said arcuate surfaces extending in opposite directions from substantially the medial portion of the apertured portion to the corresponding upper and lower lateral recesses.

8. In an indicating device of the class described, the combination according to claim 5, further provided with an escutcheon adapted for attachment to the door and in overlying relation to said bar and cam, said escutcheon having an opening adapted to permit the passage therethrough of said shaft.

9. In an indicating device of the class described, the combination according to claim 1, the said bar having a longitudinal opening therein, the said cam having a pressed out circular portion in the region of the cam's axis of rotation, said circular portion extending into and being slidably engageable with the lateral walls of the opening, whereby the bar will be guided along its operative path by said pressed out circular portion.

10. In an indicating device for use with a door having a knob and a shaft connected thereto of the type where the knob and shaft are rotatable between an intermediate neutral position and two opposite extreme positions, the combination of a reciprocable bar movable between two limiting positions, a sign carried by the bar; a cam fixedly mounted on the shaft and containing one upper and one lower arcuate surface, said arcuate surfaces being at opposite sides of the cam and having their respective centers at the axis of rotation of the cam; an upper operative surface on the cam adjacent the upper arcuate surface and sloping downwardly and outwardly therefrom, a lower operative surface adjacent the lower arcuate surface and sloping upwardly and outwardly therefrom, said operative surfaces being at opposite sides of the cam; and a follower attached to the bar and engageable with said surfaces, the follower being engageable with the said upper operative cam surface when the knob is rotated from its neutral position to one of its extreme positions to operatively lower the bar, the follower being engageable with the said lower arcuate surface when the knob is returned to its neutral position to maintain the bar against movement, the follower being engageable with the lower operative surface when the knob is moved to the other of its extreme positions to operatively raise the bar, the follower being engageable with the upper arcuate surface when the knob is returned to its neutral position to maintain the bar against movement; an escutcheon adapted for attachment to the door and in overlying relation to said bar and cam, said escutcheon having an opening adapted to permit the passage therethrough of said shaft, further provided with a casing containing therein said cam, the bar extending vertically through the casing adjacent the cam, the casing being supported between the door and the front wall of the escutcheon, the casing having a wall substantially parallel to the front wall of the escutcheon and containing an opening for said shaft.

11. In an indicating device of the class described, the combination according to claim 10, the escutcheon containing a window in registry with the sign in only one of said two predetermined positions, the casing containing four lat-

eral walls, the upper wall being below said window.

12. In an indicating device for use with a door having a keyhole, a knob and a shaft connected thereto of the type where the knob and shaft are rotatable between an intermediate neutral position and two opposite extreme positions, the combination according to claim 1, further provided with an escutcheon adapted for attachment to the door and in overlying relation to said bar and cam, said escutcheon having an opening adapted to permit the passage therethrough of said shaft, and an outer keyhole adapted for registry with said keyhole in the door, the bar having a strip attached thereto and which is in obstructing relation to said outer keyhole when the bar is in only one of said two predetermined positions, whereby the door will be prevented from being unlocked from the outside when the strip is in said obstructing position.

13. In an indicating device of the class de-

scribed, the combination according to claim 1, said bar having a plurality of holes adjacent said follower, each of said holes being adapted to operatively accommodate the follower.
